(57) CLAIM

I claim the ornamental design for a figurine bottle opener, as shown and described.

DESCRIPTION

FIG. 1 is a perspective top view of a figurine bottle opener; FIG. 2 is a front elevation view thereof;

FIG. 3 is a right side view thereof;

FIG. 4 is a rear elevation view thereof;

FIG. 5 is a left side view thereof;

FIG. 6 is a top view thereof; and,

FIG. 7 is a bottom view thereof.

The broken lines representing a bathing suit artwork and a hairstyle are for illustrative purposes only and do not form part of the claimed design.
